UNITED STATES PATENT OFFICE.

CHARLES L. REIZENSTEIN, OF PITTSBURGH, PENNSYLVANIA.

GLASS DISH AND ART OF DECORATING THE SAME.

Application filed June 11, 1924. Serial No. 719,322.

This invention relates to decorated glassware such as plates, saucers, etc.

In the art of making decorated glassware, it has for some time been common practice 5 to apply a color coat in the form of paint to the under or back surface of certain types of glassware. This generally has taken the form of bands of color. It has of course, been common practice for many years to 10 cut or press designs in glassware.

I have discovered that if I cut or press a design having concaved surfaces in the under or back surface of glassware, especially 15 crystal ware and then apply a coat of color to the cut or pressed surfaces, an unexpected and highly pleasing effect is produced when the ware is viewed from the front or through the upper surface.

The color coat when viewed through the 20 ware from the top surface accentuates the design by reflecting light from the curved surfaces thereof. The color coat because of the curved surfaces of the design is given a soft, velvety sheen instead of having a flat, 25 hard appearance as it does when applied to a flat surface. In this way, I am enabled to obtain a highly decorative effect.

I have been unable to satisfactorily illustrate the novel effect produced by the combination of the pressed or cut design and the 30 color backing coat, but for the purpose of more clearly explaining the method of carrying out this invention, I have illustrated a glass plate, decorated in accordance 35 with this invention.

In the drawings, Figure 1 is a bottom view of a plate having a border design pressed therein, suitable for utilization in 40 decorating a plate in accordance with this invention. Fig. 2 is a sectional view of the plate shown in Fig. 1. Fig. 3 is a top plan view of the plate shown in Figs. 1 and 2, Fig. 4 is a fragmentary view on an enlarged 45 scale and in section of the border portion of the plate and Fig. 5 is a sectional view taken on line 5—5 of Fig. 4, looking in the direction of the arrows.

One of the many designs which may be 50 pressed or cut and which causes the inner surface of the color coat to have the desired velvety sheen, is illustrated in Figs. 1 and 2

and consists of flutings or corrugations having smooth concaved surfaces 6 and sharply defined ridges 7. As shown in Fig. 1, these are arranged to form a band or border for 55 the plate or saucer.

To the under or outer face of these corrugations or flutes, a color coat 8 is applied. This is applied in the form of paint of any suitable or desired color and preferably 60 covers the entire pressed or cut portion. Trimming bands 9 and 10 preferably of gold paint, are applied to the front surface of the plate or saucer, one at the outer edge of the same and one, band 10, above the inner edge of the color coat. These trimming bands finish the decoration and add a pleasing touch. After the color coat and the trimming bands are applied, the ware is 65 70 75 fired in the usual manner.

Having thus described my invention, what I claim is:—

1. A transparent dish having a design on the back thereof comprising a plurality of adjoining curved surfaces and an opaque 75 coating applied to said surfaces.

2. A transparent dish having a design including a plurality of adjoining concave surfaces forming a repeated design on the back of the dish and an opaque coating of color- 80 ing material applied to said surfaces.

3. A glass dish having a border design formed by a circular band of corrugations comprising a plurality of concave surfaces separated by sharply defined ridges, an opaque color coating applied to said corrugations and a finishing band of gold paint applied to the front of said dish over the edges of said color coating. 85

4. The method of producing a design 90 upon a transparent article which consists in forming a plurality of adjoining concave surfaces on the back thereof and applying a coating of coloring material to said surfaces.

5. The method of producing a design 95 upon a glass dish which consists in forming a series of corrugations including concave surfaces and sharply defined ridges on the back of the dish, applying a coating of material to said corrugations and firing the 100 ware.

6. The method of producing a border de-

sign upon a glass plate which consists in forming a circular series of corrugations having concave surfaces separated by inwardly extending sharply defined ridges on the back of the plate, applying a coating of coloring material to said corrugations and then applying finishing bands of coloring

material to the front surface of the plate over the edges of the color coating on said corrugations.

10

In testimony whereof, I have hereunto subscribed my name this 3rd day of June, 1924.

CHARLES L. REIZENSTEIN.
